UNITED STATES PATENT OFFICE.

JAMES M. PITBLADO, OF MINNEAPOLIS, MINNESOTA, ASSIGNOR TO MINNEAPOLIS
STEEL & MACHINERY CO., OF MINNEAPOLIS, MINNESOTA, A CORPORATION.

DESIGN FOR A STREET-LAMP.

44,494.

Specification for Design.

Patented Aug. 12, 1913.

Application filed May 26, 1913. Serial No. 770,084. Term of patent 7 years.

To all whom it may concern:

Be it known that I, JAMES M. PITBLADO, citizen of the United States, residing at Minneapolis, in the county of Hennepin, State of Minnesota, have invented a new, original, and ornamental Design for Street-Lamps, of which the following is a specification, reference being had to the accompanying drawing, forming part thereof.

The figure is a perspective view of a street lamp, showing a new design.

I claim:

The ornamental design for a street lamp, as shown.

JAMES M. PITBLADO.

In presence of—

EDWARD A. PAUL,

C. H. REHFUSS.
